REFRIGERATOR

Emmanuel Dobrowsky, New York, N. Y.

Application June 23, 1936, Serial No. 86,735

1 Claim. (Cl. 99—270)

This invention relates to refrigerators, an object of the invention being to provide a refrigerator and more specifically the modern type of mechanical refrigerator with means for maintaining a partial vacuum in the food compartment. This means includes a suction pump or other suitable device which operates to draw air out of the food compartment, and this not only creates a partial vacuum in the food compartment but it also draws off odors from the food compartment so as to prevent the contamination of one article of food by odors from another or other articles of food. The principal object of the invention, therefore, is to create or maintain a partial vacuum in the food compartment which assists in the preservation of the foods in their proper condition; reduces the temperature within the food compartment, and carries off odors from the food compartment.

A further object is to provide means of this character which are automatic in their operation so that when the door of the refrigerator is opened it will, of course, permit air to rush into the food compartment and raise the pressure therein to atmospheric pressure; but when the door is again closed a partial vacuum creating means will be automatically started and automatically stopped when the pressure is lowered to the desired extent.

With these and other objects in view, the invention consists in certain novel features of construction and combinations and arrangements of parts, all of which will be more fully hereinafter described and pointed out in the claim.

In the accompanying drawing—

Figure 1 is a perspective view of my improved refrigerator showing the door to the food compartment in open position;

Fig. 2 is a fragmentary view partly in vertical section through the refrigerator and showing one means for operatively connecting the food compartment of the refrigerator with a suction pump, and this view, which is partly diagrammatic, shows the position of the parts when the desired pressure has been lowered sufficiently in the refrigerator and the pump is not operating;

Fig. 3 is a fragmentary view similar to the fragmentary sectional portion of Fig. 2, showing the position of the parts when the pump is operating;

Fig. 4 is a fragmentary view in horizontal section through a portion of the door and casing, this view being taken on the line 4—4 of Fig. 5;

Fig. 5 is a fragmentary view in vertical section

through the door of the food compartment; and Fig. 6 is a sectional elevation on the line 6—6 of Fig. 5.

The reference character A is employed to indicate generally a refrigerator which, as above stated, is of the modern mechanical type. The refrigerator A has a food compartment 1 and a door 2 to close the same. As it is necessary in my invention to have the food compartment airtight, the door and preferably the wall of the opening in the casing are provided with suitable packing material 3 to render the closure airtight when the door is closed. The food compartment 1 is provided with an air outlet chamber 4, preferably having a screened entrance end 5 and 15 constructed with a port 6 adapted to be closed by a check valve 7. This check valve is preferably of rubber or other suitable material so as to insure an airtight closure. The chamber 4 is connected to an outlet pipe 8, which is operatively connected to a suction pump 9 and this suction pump 9 is driven by an electric motor 10. It is of course to be understood that the motor and pump may be located wherever found most convenient.

In the food compartment 1 a fixed electric contact 11 is provided which is adapted to be engaged by a movable contact arm 12. This arm 12 is illustrated as pivoted between its ends on a pin 13 mounted in a bracket 14 and operatively connected at its end to a diaphragm 15 which is secured over a screened opening 16 in the wall of the casing. A spring contact brush 17 exerts pressure on one end of the arm tending to move it toward the fixed contact 11, and a stop 18 is provided in the casing to be engaged by the arm 12 to limit its movement away from the fixed contact 11. In the food compartment 1 a spring pressed plunger switch 19 is located and is movable in a casing 20 and adapted when in its inward position to close the circuit between two contacts 21 and 22. The outer end of this plunger switch 19 is in the path of movement of the door 2 so that when the door is opened the spring pressed plunger switch will be moved forwardly

40 to open the switch, and when the door is closed it will force the plunger switch inwardly to cause the same to engage the contacts 21 and 22 and close the circuit. I have illustrated diagrammatically in Fig. 2 an electric circuit which might 45 be employed in connection with my improved apparatus. In this circuit 23 and 24 indicate lead-in wires from the ordinary city service. The wire 24 is connected to a pole 25 of the motor 10 and a wire 26 connects the other pole 27 of the motor 50

with the fixed contact 11. The contact brush 17 is connected by a wire 28 with the contact 21 and the other contact 22 is connected to the lead wire 23.

5 The operation of the mechanism above described is as follows: When the door 2 is opened the air from outside will of course rush into the food compartment and equalize the pressure within and without the same. When the door is 10 open, therefore, it is desired that there will be no operation of the pump and this is prevented by reason of the fact that the plunger switch will spring outwardly and maintain open circuit as long as the door is open. Further, when the 15 door is closed, the pressure in the compartment is raised the diaphragm 15 will return to a straight or normal position, as shown in Fig. 3, which movement causes the contact arm 21 to engage the fixed contact 11. The circuit will not be closed until 20 the door is closed as above explained. As soon as the door is closed and the circuit to the motor 10 is closed, this motor will operate the pump 9 to draw air out of the refrigerator past the check valve 7, and when the pressure in the refrigerator 25 is sufficiently lowered or, in other words, when the desired partial vacuum is reached, the diaphragm 15 will be drawn inwardly to the position shown in Fig. 2 of the drawing, which will result in causing the contact arm 12 to move 30 away from the contact 11 and open the circuit, thus stopping the motor until for some reason or other the pressure within the refrigerator should again rise.

As it is well known that it would be difficult to 35 open the door of the refrigerator when a partial vacuum is in the food compartment, it is necessary or at least desirable to provide a means which will permit air to enter the compartment when the latching means of the door is operated. 40 This means is shown in detail in Figs. 5 and 6 of the drawing. I have illustrated a latch box 29 secured to the outer face of the door and in which a latch bar 30 is mounted to turn and is adapted to engage a suitable keeper 31 on the 45 casing. An operating crank handle 32 is fixed to the latch bar 30 and carries within the box 29 a crank arm 33. The door 2 of the food compartment is provided with an opening 34 communicating with the interior of the latch box 29 and a valve 35 normally closes this opening. A small 50 air duct 36 is provided in the door communicating with an opening 34 in the latch box. The valve 35 is preferably of the flexible disk type, as shown, secured to the door at its upper por-

tion by means of a pin or rivet 37. The central portion of this valve is preferably thicker than the rest of the valve and the thinner edge portion of the valve normally covers the air duct 36. The crank arm 33 may engage the central portion 5 of the valve and operate to assist in closing the same and holding the same in closed position. A chain or other flexible connecting device 38 connects the lower edge portion of the valve 35 with the arm 33 so that when the handle 32 is 10 moved outwardly and upwardly to move the latch bar for engagement with the keeper 31, the arm 33 operates to draw the flexible edge portion of valve 35 from over the air duct 36. Thus a certain amount of air will rush into the opening 34, 15 facilitating the release of the valve 35 and the continued movement of the handle 32 will draw the valve 35 away from the opening 34 allowing additional air to rush into the food compartment to raise the pressure therein and to make it easy 20 to open the door. When the door is closed the valve 35 will of course close the opening 34 and the duct 36 so that the pressure within the food compartment can be reduced as desired.

While I have illustrated and described what I 25 believe to be the preferred embodiment of my invention, it is obvious that various slight changes may be made with regard to the form and arrangement of parts without departing from my invention, and hence I do not limit myself to the 30 precise details set forth but consider myself at liberty to make such changes and alterations as fairly fall within the spirit and scope of the claim.

I claim:

The combination with a refrigerator having a food compartment and a door thereto, a pump operatively connected to the compartment and adapted to maintain a partial vacuum therein, said door having an air inlet opening, a valve 40 normally closing said opening, a latch on the door operatively connected to the valve and adapted to open the valve when the latch is moved to open position, said door having an air entrance 45 duct communicating with the air inlet opening in the door normally closed by the edge portion of the valve, and a flexible device connecting the latch with the edge portion of the valve whereby the edge portion of the valve will be first lifted 50 to open the duct when the latch mechanism is operated.

EMMANUEL DOBROWSKY.
